SPINNING UNIT

Whitworth F. Bird, Springfield, Pa., assignor to
 Collins & Aikman Corporation, Philadelphia,
 Pa., a corporation of Delaware

Application October 26, 1933, Serial No. 695,255

5 Claims. (Cl. 118—49)

This invention relates to spinning units; and it has reference more particularly to spinning units for cap spinning or twisting machines wherein the roving or the thread, in leaving the draft or delivery rolls of the machine, passes downward exteriorly of the cap and around the bottom edge of the latter enroute to a coaxially-supported rotating and traversing bobbin, and twisted into yarn by incidentally induced gyration about the cap. Due to excessive ballooning of the gyrating segment of the roving or thread and the drag imposed upon it as it turns sharply about the lower edge of the cap under the high rotative speed of the bobbin, it is weakened and often strained beyond its tensile strength to the point of rupture. Furthermore, due to air friction and to impact of the roving or thread with the separators usually employed in the spinning or twisting machines between adjacent spinning units of a series, many of the component fibers of the roving or thread become detached or displaced, and, as a result, they are either released or not properly incorporated during the twisting of the yarn. Another difficulty peculiar to cap spinning is that, under the terrific air friction attending rapid rotation of the bobbin, the outer layers of the yarn on the latter become frayed with consequent further disturbance and displacement of the fibers. Yarn formed under the described conditions is rough and "hairy", and resists subsequent withdrawal from the bobbin by reason of the entanglement of its loose and projecting fibers. Such yarn moreover gives rise to considerable trouble in weaving, and fabric woven therefrom is invariably unsatisfactory from the standpoint of appearance and finish, and often requires additional processing before it is commercially acceptable.

My invention is directed in the main toward overcoming the several drawbacks which have been pointed out, that is to say: it has for its chief object, the provision of simple and reliable means in connection with cap spinning units whereby the ballooning of the roving or thread is effectively controlled and release or displacement of the component fibers by impact and air friction minimized, and whereby the gyration of the free segment is more positively induced with easement of the strain on the roving or thread and assurance against the possibility of its being ruptured during spinning, and with the further assurance of a markedly improved twisted product which is free of the usual characteristic defects of cap spun yarns.

Another advantage of my invention is that it

makes feasible cap spinning at higher speeds than heretofore possible, with corresponding increase in production.

Further objects and attendant advantages of this invention will be manifest from the detailed description following of the attached drawing, wherein Fig. I is a vertical sectional elevation of a cap spinning or twisting unit embodying the present improvements, the parts of the unit being shown in the positions which they respectively occupy at the completion of a spinning or twisting cycle.

Fig. II is a view like Fig. I showing the parts of the unit in the positions which they occupy at the beginning of a spinning or twisting cycle;

Fig. III is a cross section taken as indicated by the arrows III—III in Fig. II.

With more specific reference to these illustrations, the numeral 4 designates the vertical spindle of the spinning or twisting unit, said spindle being threaded at its lower end as at 5 and screwed into the stationary spindle rail 6 as usual. The upper end of the spindle 4 is tapered, as at 7, to support an upwardly-removable self-centering stationary cap 8 which has an axial bore 9 in the rounded top of its downwardly flaring hollow conical body portion 10 fitting the taper 6 of said spindle. The bottom edge 11 of the cap 8 is suitably smoothed to preclude chafing of the roving or thread 12 which is being twisted as it passes from the drive or delivery rolls (not shown) of the spinning or twisting machine to the bobbin 13 whereon the twisted yarn is collected. The bobbin 13 is of the axially-hollow type and fits over the tubular stem or sleeve 14 of a whirl 15 which revolves about the stationary spindle 4, and which, at its lower end, is formed with a pulley 16 for coordination with a driving belt 17. After common practice, the whirl 15 is supported by a traversing rail 18, which, during each spinning or twisting cycle, is moved up and down in any suitable manner to determine any desired type of wind of the yarn on the bobbin 13. As shown, the bobbin 13 rests on the supporting surface 19 of the whirl 15, and has a key drive connection at 20 with said surface.

In order to adapt a spinning unit such as described to the purposes of my invention, I form the whirl 15 with an open-topped upward hollow cylindric cup-like extension 21. This extension 21 is illustrated as having a height substantially equal to that of the bobbin 13, but this dimension may be varied in practice accord-

ing to the style of bobbin and kind of material being spun or twisted, for attainment of the best results. The extension 21, moreover has a diameter which determines a substantial annular interval 22 around the bobbin 13 capable of telescopically receiving the cap 8, as shown in Fig. II, incident to the traversing movement of the whirl 15.

In the operation of the unit, the roving or thread 12 enroute downward from the draft or delivery rolls (not shown) of the spinning or twisting machine, passes over the top edge 23 of the cup-like extension 21 of the whirl 15 and into the interval 22 between the wall of said extension and the cap 8, eventually turning sharply about the lower edge of said cap into tangential relation with the bobbin 13 as shown in Fig. III. Under the high speed rotation of the bobbin 13 and by virtue of frictional contact with the bottom edge 11 of the cap 8, the roving or thread 12 is caused to gyrate about said cap and is thereby twisted before it is taken by the bobbin. It is however to be noted here that, in passing to the bobbin, the roving or thread 12 is restrained against excessive ballooning as a consequence of contact with the inner surface of the cup-like extension 21 of the whirl 15. Thus in effect, the extension 21 constitutes a guard about the bobbin 13, rotating in unison with the latter and thereby effectively assisting gyration of the free segment of the roving or thread 12. As a result of this cooperation of the cup-like extension of the whirl, the roving or thread 12 is relieved of undue strain such as might tend to rupture it, while the possibility of disturbance or displacement of its component fibers by air friction or beating is reduced to a minimum. A further advantage resulting from the guard extension 20 of the whirl 15 is that a "dead" air space 22 is provided around the bobbin within the extension, the air necessarily partaking of the rotary velocity of the whirl and thus precluding loosening of the fibers of the outer layers of the twisted 45 yarn on the bobbin by counteracting frictional action of the air.

My invention is obviously applicable to spinning units wherein the cap is traversed in respect to the bobbin with attainment of advantages equal in all respects to those hereinbefore pointed out in connection with the illustrated organization.

Having thus described my invention, I claim:

1. In a spinning unit for cap spinning or twisting machines, a non-rotating spindle; a coaxial whirl for the bobbin onto which the twisted yarn is wound; a coaxial cap non-rotatively supported by the spindle, said cap and whirl having relative traversing movement; and 60 a revolving annular guard capable of telescopically receiving the cap and functioning as a contact surface about the bobbin to restrain the

roving or thread against excessive ballooning as it passes downward exteriorly of the cap and beneath the bottom edge of the latter on its way to the bobbin, and to assist gyration of the roving or thread around the cap.

2. In a spinning unit for cap spinning or twisting machines, a non-rotating spindle; a coaxial whirl for the bobbin onto which the twisted yarn is wound; a coaxial cap non-rotatively supported by the spindle, said cap and whirl having relative traversing movement; and an annular guard revolving in unison with the whirl capable of telescopically receiving the cap and functioning as a contact surface about the bobbin to restrain the roving or thread against excessive ballooning as it passes downward exteriorly of the cap and beneath the bottom edge of the latter on its way to the bobbin, and to assist gyration of the roving or thread around the cap.

3. In a spinning unit for cap spinning or twisting machines; a non-rotating spindle; a coaxial cap non-rotatively supported by the spindle and a coaxial whirl for the bobbin onto which the twisted yarn is wound, said whirl having a hollow open-topped cylindric upward cup-like extension capable of telescopically receiving the cap and functioning as a revolving contact guard about the bobbin to restrain the roving or thread against excessive ballooning as it passes downward exteriorly of the cap and beneath the bottom edge of the latter on its way to the bobbin, and to assist gyration of the roving or thread around the cap.

4. In a spinning unit for cap spinning or twisting machines, a non-rotating spindle; a coaxial whirl for the bobbin onto which the twisted yarn is wound; a coaxial cap non-rotatively supported by the spindle, said cap and whirl having relative traversing movement; and a cylindric guard revolving in unison with the whirl and defining a circumferential interspace around the bobbin in which the entrained air is obliged to partake of the rotative velocity of the whirl, thereby counteracting frictional action of the outer air and preventing fraying of the outer layers of yarn on the bobbin.

5. In a spinning unit for cap spinning or twisting machines, a stationary spindle; a coaxial cap non-rotatively supported by the spindle; and a coaxial traversing whirl for the bobbin onto which the twisted yarn is wound, having a hollow cylindric open-topped upward cup-like extension capable of telescopically receiving the cap with provision of a circumferential interspace around the bobbin entraining air which is obliged to partake of the rotative velocity of the whirl, thereby counteracting frictional action of the outer air and preventing fraying of the outer layers of yarn on the bobbin.

WHITWORTH F. BIRD.
